UNITED STATES PATENT OFFICE.

FERDINAND P. SCHEIDEMANTLE, OF ELLWOOD CITY, PENNSYLVANIA.

BRAD-DRIVER.

1,330,283.

Specification of Letters Patent. Patented Feb. 10, 1920.

Application filed May 1, 1919. Serial No. 293,971.

To all whom it may concern:

Be it known that I, FERDINAND P. SCHEIDEMANTLE, citizen of the United States, residing at Ellwood City, in the county of 5 Lawrence and State of Pennsylvania, have invented certain new and useful Improvements in Brad-Drivers; and I do declare the following to be a full, clear, and exact 10 description of the invention, such as will enable others skilled in the art to which it appertains to make and use the same.

My invention relates to the art of picture framing and more particularly to a novel 15 form of tool for driving brads in the frame to retain the glass, mat, picture and backing, or other contents of the frame in place. Heretofore, difficulty has been encountered in driving the brads in the frame and this 20 has necessitated the expenditure of a great deal of time, and the object of the present invention is to provide a simple and inexpensive, yet a highly efficient, rapid, and reliable tool for driving the brads, by simply moving two handles together.

25 With the foregoing in view, the invention resides in the tool hereinafter fully described and claimed, the invention being illustrated in the accompanying drawing.

Figure 1 is a side elevation partly in section, showing the tool in use.

Fig. 2 is a perspective view of the tool removed from the frame.

In the drawing above briefly described, the numeral 1 designates a flat bar having 25 one end bent at a right angle thereto as seen at 2 and shaped to form a handle 3 to which a flat spring 4 may be secured. A substantially S-shaped lever 5 crosses the lower end 2 of the handle 3 and is fulcrumed 40 thereto by a rivet or the like 6, the upper end of said lever being shaped to form a handle 7 against whose inner side the spring 4 bears to normally hold said lever in a retracted position. The lower end 8 of 45 the lever 5 is widened, preferably by having an extra thickness of material 9 riveted thereto, and said end forms a driving nose for the brads 10 as seen in Fig. 1.

A slide 12 is mounted on the bar 1 and 50 is held against lateral tilting by the flat shape of the latter, and by means of a set screw 13 threaded in the upper end of said slide and adapted to engage sockets 14 in the upper edge of the bar, said slide may

be held in adjusted position. The slide 12 55 projects below the bar 1 and is provided with a cushioning block 15 of any preferred material which may be secured thereto by countersunk rivets or the like 11. The cushion 15 contacts with the outer edge of the picture frame 16, the lower end of the lever 5 abuts the head of the brad 10, and by simply moving said lever toward the handle 3, by a single movement of the operator's hand, the brad will be driven in place. The 60 slide 12 is adjusted along the bar according to the width of the frame.

From the foregoing, taken in connection with the accompanying drawings, it will be obvious that although my invention is of extremely simple and inexpensive nature, it will overcome difficulties heretofore encountered and will consequently be a great saver of time. Since probably the best results are obtained from the details disclosed, 70 they may well be followed, but within the scope of the invention as claimed, numerous minor changes may well be made.

I claim:

1. A tool for driving brads in picture 80 frames comprising a bar having one end bent at a right angle thereto and shaped to form a handle, an approximately S-shaped lever crossing the lower portion of said handle-forming end of said bar and fulcrumed thereto, the upper end of said lever forming a handle for coöperation with the first named handle in moving said lever around its fulcrum, the lower end of said lever forming a brad driving nose, a slide 85 mounted on said bar, and means for holding said slide in adjusted position, said slide being adapted to engage the outer edge of the picture frame, whereby movement of the lever will drive a brad into the inner 90 edge of said frame.

2. A tool for driving brads in picture 100 frames, comprising a flat-sided bar having one end bent at a right angle thereto and shaped to form a handle, an approximately S-shaped lever crossing the lower portion of said handle-forming end of said bar and fulcrumed thereto, the upper end of said lever forming a handle for coöperation with the first named handle in moving said lever 105 around its fulcrum, the lower end of said lever forming a brad driving nose, a slide mounted on said bar and held against lateral

tilting by the shape thereof, said bar having spaced sockets in its upper edge, a set screw threaded in the upper end of said slide for engagement with said sockets to hold the slide in adjusted position, and a cushioning block on the lower end of said slide adapted to abut the outer edge of the

picture frame, whereby movement of the aforesaid lever will drive a brad in the inner edge of said frame.

10

In testimony whereof I have hereunto set my hand.

FERDINAND P. SCHEIDEMANTLE.
